UNITED STATES PATENT OFFICE.

JOHN CUMMINGS, OF NEW YORK, N. Y.

BRIDLE-BIT.

No. 909,160.

Specification of Letters Patent.

Patented Jan. 12, 1909.

Application filed March 25, 1908 Serial No. 423,035.

To all whom it may concern:

Be it known that I, JOHN CUMMINGS, a citizen of the United States, residing in borough of Brooklyn, city and State of New York, have invented certain new and useful Improvements in Curbers or Controllers for Bridle-Bits, of which the following is such a full, clear, and exact description as will enable any one skilled in the art to which it applies to make and use the same, reference being had to the accompanying drawings, forming part of this specification.

My invention relates to the general type of curbers or controllers for bridle-bits for horses, in which a band is operatively connected with the bit and is thereby caused to act upon a certain part of the horse's head, whenever the reins are pulled upon.

The principal object of the present invention is to facilitate attaching the curber to or detaching it from the ordinary bridle-bit, at the same time rendering the device absolutely proof against detachment when once in place.

Other objects of the invention are to provide a securer means of attaching the nose straps to the curber, and to make a smooth and better joint between the nose band and the terminal pieces of the same.

With these and other objects in view, my invention consists in the various novel and peculiar arrangements and combinations of the several different parts of the device, all as hereinafter fully set forth and then pointed out in the claim.

I have illustrated a type of my invention in the accompanying drawings, wherein;

Figure 1 is a perspective view of my improved device with the nose strap of a bridle attached thereto. Fig. 2 is an enlarged inside view of one of the terminal pieces or plates of the nose band shown as detached and with the mouth piece of a sectional or jointed bit, shown in dotted lines, in perspective and illustrating the manner of attaching or detaching the terminal piece and the bit.

Referring to the drawings in which like numbers of reference designate like parts throughout, 1 is a nose band made of suitable resilient metal, having the main central portion thereof covered or incased with a piece of soft material 2 to protect the animal's nose from the metal band. Each end of the nose band 1 is provided with a terminal piece or plate 3 comprising a loop 4,

which is preferably of an oval shape with the greatest diameter extending longitudinally of the piece. This loop 4 is for receiving the bit indicated at 5 in dotted lines and at one side of the loop, preferably the under side 60 when the parts are in position, is formed an opening or cut-away place 6 through which the bit is introduced or out of which it is passed in detaching the parts.

The bit 5 is of a varying diameter, the 65 larger part being toward each outer end and the contracted part toward the center where the bit is jointed at 7 by means of an eye on the inner end of each of the bit sections passing one through the other in a manner well-known.

The two terminal pieces 3 when united with the nose piece 1, as shown in Fig. 1, are readily placed over the bit, by drawing the two end pieces toward each other so as to 75 bring them nearer together, and then passing the reduced central portion of the bit through the respective openings 6 of the two loops, and then releasing the terminal members which at once spring to the outer ends 80 of the bit against the end or cheek pieces 8 thereof. As the outer ends of the bit are of much greater diameter than the openings 6 in the loops, it is impossible for the bit and the controller to become detached from each 85 other and particularly when the same are placed upon the horse and in use. As the openings 6 are upon the lower sides of the loops, the upper and unbroken sides thereof lie practically in contact with the bit when 90 placed on the horse so that there is not even a tendency of the bit to enter the openings 6, the mere weight of the device keeping the bit away from the openings.

In order to separate the curber and the bit, 95 the terminal or end pieces 3 are drawn together and brought toward the center of the bit, so that the reduced portion of the latter may readily pass out of the respective openings 6 of the loops. It will be noted that in 100 either mounting or dismounting this curber and the bit, that it is unnecessary to detach the reins from either end of the bit, as is the case in many of the curbers of this class now on the market. This is an important advantage in the use of my improved device and is one of its chief objects.

The attaching ends of each of the terminal pieces 3, which are preferably formed of cast metal, are each provided with an extension 110

9, and the inner face of each is formed with a wide groove or recess 10 into which fits the end 11 of the nose band 1, so that the same lies flush with the terminal members to which it is attached by means of suitable rivets 12 passing through perforations 13 formed in the material of the terminal part. In addition to this presenting a smooth part to bear against the cheek of the animal, it also materially strengthens the joint between the nose band and the terminal piece.

Each of the terminal pieces 3 is formed upon its upper edge toward its inner end with an integral eye 14 which is cast with the part 15 3 and is preferably inclined toward the outer end of the terminal piece and is adapted to receive the nose strap 15, which extends upwardly to the head band of the bridle and serves to support the band in proper place 20 on the horse's nose. This is an improvement over the forms of these curbers in which the nose strap is sewed or in some way attached to the leather part of the curber compared

with which my construction has obvious advantages.

Having thus described my invention, what I claim and desire to secure by Letters Patent is:—

A curber or controller comprising, a resilient band, end pieces having flanged recesses in their inner faces in which the ends of the band are secured flush with said inner faces, loops at the upper forward corners of the end pieces for the purpose stated and loops at the rear ends of the end pieces provided at the lower sides of their forward portions with openings to pass over the smaller portions only of the members of a snaffle bit, substantially as set forth.

In testimony whereof, I have hereunto set 40 my hand in the presence of the two subscribing witnesses.

JOHN CUMMINGS.
